UNITED STATES PATENT OFFICE.

STERRETT E. McNULTY, OF WASHINGTON, DISTRICT OF COLUMBIA.

WINDOW-PROTECTING ATTACHMENT.

1,230,197.

Specification of Letters Patent. Patented June 19, 1917.

Application filed October 1, 1915. Serial No. 53,604.

To all whom it may concern:

Be it known that I, STERRETT E. McNULTY, a citizen of the United States, residing at Washington, in the District of Columbia, 5 have invented certain new and useful Improvements in Window-Protecting Attachments, of which the following is a specification.

This invention relates to improvements in 10 means for preventing the ingress of flies, insects and obnoxious substances through windows in which fly screens have been arranged, and the invention is specifically designed to close the gap between the screen 15 frame and the window sash, and to permit of the adjustment of the window sash.

When one of the common fly screen frames is positioned in a window casing and the inner window sash raised, it is possible for flies or other insects to enter the 20 room through the gap formed between the opposing sides of the inner sash and the screen frame. The clearance between the sash and the screen frame is made freer by 25 the partial lowering of the inner sash.

My invention provides simple means for closing the gap between the screen frame and the inner sash frame, and is so constructed as to permit of the ready adjustment 30 of the inner sash frame. The invention is embodied in a frame for holding a yieldable strip, which frame is provided with end members adapted to engage the parting strips of the window casing and 35 adjustable relative to the strip holding frame, and detachable relative to the parting strips.

With the above and other objects in view the invention consists of certain new and 40 useful constructions, combinations and arrangements of parts, clearly described in the following specification and fully illustrated in the accompanying drawings, in which:—

45 Figure 1 is a vertical sectional view of a window casing and companion window sashes, showing the improved device in operative position.

Fig. 2 is a side view of the improved device.

50 Fig. 3 is a top plan view thereof.

Fig. 4 is a detail end view, partly in section, and on an enlarged scale, showing one of the connecting members or legs, and the key-hole slot. 55

Fig. 5 is a similar view, showing the opposite side.

Fig. 6 is a side elevation of a modified form.

Fig. 7 is a detail plan view of end portions of the members of the modified form. 60

Fig. 8 is a transverse sectional view of another modified form.

Fig. 9 is a plan view thereof.

Fig. 9^a is a detail end view of a supporting leg. 65

Fig. 9^b is a similar view of another supporting leg.

Fig. 9^c is a detail sectional view of a clamping tongue construction. 70

Referring to the accompanying drawings 5 designates the lower member or sill of the window casing, 6 and 7 the parting strips, 8 the inner sash frame, 9 the outer sash frame, and 10 and 11 the inner and 75 outer sash guiding strips, respectively.

The usual screen frame 12 is positioned between the outer guiding strips 11 and the parting strips 6 and 7. When the inner sash frame 8 is in the position shown in Fig. 80 1, that is with its lower member below the upper horizontal member of the screen frame, a gap or clearance will be opened through which flies or other insects may gain admission to the room. 85

To prevent flies and other insects from entering the space between the inner window sash and the screen frame, I arrange a flexible strip 14 on a holding frame 15, and secure the ends of this holding frame to the parting strips 6 and 7, so that the flexible strip 14 will lie in a horizontal plane and its outer edges will project beyond the vertical plane of the window glass sections of the inner and outer sash frames. 90

The flexible strip holding frame 15 consists of a lower bar member 16, an intermediate top bar member 17, and oppositely extending upper end bar members 18 and 19, each of which is formed with a pendant leg 110 or attaching member 20. The bars 16, 17, 18 and 19 are formed of strip stock and are 95

each provided with angular longitudinal flanges F, located on opposite sides thereof, whereby the bar is substantially U-shaped in cross section. The flanges F of the lower bar 16 project downwardly, and the flanges F of the upper bars 17, 18 and 19 project upwardly. The pendant legs or attaching members 20 are formed on the bars 18 and 19 by bending the end portions of said bars, 10 without flattening the flanges of said end portions. In this way each leg or attaching member 20 is provided with spaced flanges f and in the space thus provided in each leg one of the parting strips is adapted to 15 snugly fit.

Each leg or attaching member 20 is formed with an opening 21, which may be a circular opening, but which is preferably a key-hole opening, with its larger end portion 21' located near the lower terminal of the leg. The frame 15 is supported on the parting strips 6 and 7 by means of screws, brads or other headed fastening means, 22, the heads of which are smaller than the 20 portions 21' of the leg openings 21, and the shanks of which are smaller than the portions 21'' of said leg openings 21. By placing the larger end portions 21' of said leg openings 21 in registration with the heads 30 of the fasteners 22 and forcing the legs against the parting strips and then forcing the legs downwardly so that the shanks of the fasteners will enter the smaller portions of the leg openings the holding frame 35 may be secured to the parting strips. By reversing this action the holding frame 15 may be readily detached from the parting strips.

The flexible strip 14 is preferably a thin 40 rubber strip, suitably reinforced by canvas, but it may consist of felt, canvas or other material. This strip 14 is secured between the lower bar 16 and the upper bars 17, 18 and 19 by means of screws or fasteners 23 and 45 24. The screws or fasteners 23 project through openings formed in the intermediate bar 17 and the lower bar 16, and the screws or fasteners 24 project through longitudinal slots 25 formed in the bars 18 50 and 19 and then through the lower bar 16. The screws or fasteners 23 and 24 are each provided with a nut or clamping member 26, and by tightening said nuts or clamping members 26 on the screws or fasteners 23 55 and 24 the upper and lower bars may be rigidly locked to each other and the flexible strip tightly secured between said upper and lower bars. By adjusting the relation of the end bars 18 and 19 relative to the 60 intermediate bar and the bottom bar the length of the holding frame may be increased or diminished, so that the holding frame may be made adjustable to fit any window casing.

The flexible strip 14 is considerably wider 65 than the bars or the holding frame, so that it will project laterally of the holding frame a sufficient distance to contact with the glass sections of the window sashes, and thus prevent the passage of flies or other insects. 70

By the use of the intermediate bar and the method of rigidly connecting the intermediate bar to the lower bar, a rigid central body is provided for the holding frame.

In Figs. 6 and 7 I show a modified form 75 of the invention, wherein the holding frame is made up of a single lower bar 27 and a single upper bar 28, each bar being formed with a pendant leg or attaching member 29, and being also formed with a longitudinal slot 30 for each clamping screw or device, by means of which the upper and lower bars are clamped to each other and the flexible strip 32 clamped between the bars, in the manner previously set forth. 80 85 The flexible strip is also formed with longitudinal slots adapted to register with the longitudinal slots of the bars 27 and 28, so that the necessary relative longitudinal adjustment between the bars 27 and 28 can 90 be effected against the flexible strip.

In Figs. 8 and 9 I show a modified form 95 of construction, wherein the slot and bolt adjustment is eliminated, by the use of two bars, one of which slides within the other. Referring to these figures 35 designates the lower bar, which is formed with overlying inset flanges 35^a and 35^b, the inner edges of 100 which are spaced apart, so that the bar 35 is substantially C-shaped in cross section. The bar 35 receives the side wings 36^a and 36^b of the upper bar 36, which is provided with a central offset portion 36^c which is adapted 105 to slide between the opposing edges of the inset flanges 35^a and 35^b. The bar 36 is inserted endwise in the bar 35 and is adapted to slide without limit therein, so that the two bars, when interfitted, may be extended 110 on each other the full limit of their sliding connection.

Against the upper side of the frame thus formed by the interfitting bars 35 and 36, the flexible strip 37 is positioned, and is suitably clamped to the central offset portion 36^c of the bar 36, by the plate 38 and 115 the connecting rivets 39. Against the lower side of the holding frame bar 35 the flexible strip 40 is disposed, being clamped to the bar 35 by the plate 41 and the connecting rivets 42. The plates 38 and 41 are preferably transversely curved, so as to dish or curve the flexible strips 37 and 40. The upper face of the bar 36 and the lower face of the bar 35 may also be curved, as shown 120 in cross section in Fig. 8.

To retain the screen against outward displacement I provide bracket members or stops 43, which are secured to the plate 38 125

by the rivets 39, and which have pendant screen engaging arms 44 projecting outwardly of the strips 37 and 40.

Owing to the deflection of the strips 37 and 40 toward each other, the confronting edges of the strips will contact with each other, as shown in Fig. 8, so that there will be no space left between the strips.

The flexible strip 37 frictionally resists the free sliding action of the bars 35 and 36 on each other, by its engagement with the upper faces of the inset flanges 35^a and 35^b, and by its engagement with the flexible strip 40.

15 The bar 35 is formed with a terminal leg 45, which is provided with a keyhole opening 45^x; and the bar 36 is formed with a terminal leg 46, which is provided with a keyhole opening 46^x, as shown in Figs. 9^a and 9^b, respectively.

The manner in which the flexible strip is secured to the bar 36, and the clamping bar 38 secured to said bar 36, is shown in Fig. 9^c; a similar construction being carried out with reference to bar 35. The bar 38 is formed with a tongue 38^x which is extended through a small opening 36^x formed in the bar 36 and a small opening 37^x formed in the strip 37, and is then bent against the face of the bar 36, thus locking the bars 36 and 38 to each other and the flexible strip therebetween.

Having described my invention, I claim and desire to secure by Letters Patent:—

35 1. A device for closing the passage of a window against insects, consisting of a holding frame, means for securing the holding frame to the parting strips of a window casing, and a flexible strip carried by the holding frame and having free longitudinal yielding edge portions projecting laterally of the holding frame for engagement with the window sashes.

40 2. A window protecting device consisting of a holding frame, a flexible strip carried by the holding frame and having yieldable longitudinal edge portions projecting laterally of the holding frame, said frame including relatively adjustable supporting members for attaching the frame to the parting strips of a window casing.

45 3. A window protecting device consisting of a holding frame, a flexible strip carried by the holding frame and having freely yieldable longitudinal edge portions projecting laterally of the holding frame and adapted to slidably contact with the panes of window sashes, and means for securing the ends of said holding frame to the window casing to support said strip for slidable contact with the window sashes.

50 4. A window protecting attachment consisting of companion holding frames slidably connected to each other, and a flexible

strip secured to each holding frame, the edges of said flexible strips being held close to each other, said strips being adapted to slide on each other when the frames are shifted on each other.

5. A window protecting device consisting of a flexible strip, a pair of holding bars narrower than the flexible strip, means for clamping the strip to the bars, and means on said bars for supporting the bars and the strip in horizontal position in a window casing, said means having an extensionable connection with said bars.

6. A window protecting device consisting of companion members interlocked to each other against lateral displacement and for relatively free longitudinal movement on each other, a flexible strip secured to each member and having freely yielding longitudinal side portions projecting in opposite directions from said member, and means for supporting said members against a window sash.

7. A window protecting device consisting of companion members slidably interlocked with each other for relative longitudinal movement on each other and against lateral displacement, flexible strips disposed against said members, and bars disposed against said flexible strips and interlocked with said members to hold the flexible strips thereto.

8. A window protecting device consisting of a holding frame comprising companion bars, one of said bars being C-shaped in cross section and the other bar slidably fitting in said C-shaped bar, flexible strips secured to said bars, and means for attaching the outer end of each bar to the parting strip of a window casing.

9. A window protecting device consisting of a holding frame comprising companion bars, one of said bars being formed with a centrally offset portion and the other bar having overlying flanges slidably engaging the wings of said first bar, and flexible strips secured to said bars and projecting outwardly thereof.

10. A window protecting device consisting of a holding frame comprising companion bars, one of said bars having inset flanges the edges of which are spaced from each other, the other bar being slidably interfitting in said first bar, a flexible strip secured to the lower side of the first bar, and a flexible strip secured to the central portion of the second bar and adapted to exert pressure against the inset flanges of the first bar.

11. A window protecting device consisting of a holding frame comprising slidably interfitting bars, a flexible strip secured to each bar and projecting laterally thereof, and means for supporting said bars and strips on a window casing.

21
12. A window protecting device consisting of a bar having tongues stamped out of the body thereof, a flexible strip disposed against said bar, and a second bar disposed against said flexible strip and having openings to receive said tongues, said tongues

being extended through said strip and said opening and bent downwardly against said second bar to lock the two bars to each other and the flexible strip therebetween.

In testimony whereof I affix my signature.
STERRETT E. McNULTY.
